Specification of Letters Patent.

Patented Jan. 4, 1921.

Application filed February 12, 1917. Serial No. 147,991.

To all whom it may concern:

Be it known that I, OSCAR V. GREENE, a citizen of the United States, and a resident of Cleveland, county of Cuyahoga, and State of Ohio, have invented a new and useful Improvements in Headlights, of which the following is a specification, the principle of the invention being herein explained and the best mode in which I have contemplated applying that principle, so as to distinguish it from other inventions.

The present improvements constitute in part the practical development of the head-light for vehicles and the like which forms the subject matter of my application filed July 15, 1916, Serial No. 109,515, and in part a modification in the principle of construction of such head-light. The practical developments include, among other things, an improved mounting for the several reflector sections which constitute a feature of my previous construction, the provision of improved operating means for adjusting the position of the movable portion of such reflector, the provision of an adjustable mounting for the electric lamp bulb which forms the source of light, the construction of such lamp bulb itself, and other features to which attention will be more specifically directed in the course of the detailed description which follows. The modifications in construction relate more especially to the relative disposition of the several reflector sections with respect to the light source, and the angular relation of their axes to each other. These modifications will likewise be set forth in detail in the following description, and all the aforesaid features of improvement particularly pointed out in the claims.

The annexed drawings and the following description set forth in detail certain mechanism embodying the invention, such disclosed means constituting, however, but one of various mechanical forms in which the principle of the invention may be used.

In said annexed drawing:

Figure 1 is a front elevational view of the reflector proper with its mounting and certain accessory parts, but without the inclosing casing; Fig. 2 is a broken rear elevational view of the same; Fig. 3 is a central vertical section of the head-light complete, save for the glass which closes the front of the casing; Fig. 3^a is a front elevation of a detail; Fig. 4 is a top plan view, and Fig. 5 is a side

elevation, both more or less diagrammatic in character, showing the relative location and disposition of the reflector sections; Fig. 6 is a view of an electric lamp bulb specially designed for use with my improved head-light; Fig. 7 illustrates in outline the forward portion of an automobile equipped with my improved head-light, and shows more especially the operating means provided in connection therewith; Fig. 8 is a broken sectional view, on larger scale, of said operating means; Fig. 9 is a plan view of a portion of the same, the portion being indicated by the line 9—9, Fig. 8; while Figs. 10 and 11 are transverse sectional views of such portion taken on the planes indicated by the lines 10—10 and 11—11, Fig. 9, respectively.

As illustrated in Fig. 3, my improved head-light involves no modification of the outer shell or casing 1, which is there shown as of the usual conical or basin-like shape, the open face of which is covered over with a glass shield (not shown) suitably attached to the edge 2 of the casing. The entire reflector, as well as the lamp or lamps and other parts employed in connection therewith, are designed to be carried by a separate framework that is adapted to be inserted in such typical casing and there secured, so that the reflector in a lamp at present in use may be readily replaced with my improved reflector.

The frame in question comprises an approximately annular portion 3, which fits snugly within the open end of the casing 1, and is provided with three curved radial ribs, 4, 4 and 5, the first two of which lie in the same horizontal plane, while the third lies in a vertical plane above such horizontal plane. By means of these ribs, I support in fixed position two similar quarter segments 7, 7 of a reflector of general parabolic form. Each of these sections is held in place by means of a screw 8 at its innermost corner, while its lower edge rests on a ledge 9 on the corresponding horizontal rib 4, and its front edge abuts against the back of the annular frame member 3, a set-screw or lug 10 serving as a stop to prevent it from buckling. A flat, slightly wedge-shaped member 11 adjustably secured to the vertical rib 5 near its forward end by means of a set screw 12, serves to simultaneously secure both of the two reflector sections in question in close-fitting engagement with the

front annular frame member and with the respective horizontal ribs, the result being to insure the preservation of the proper curvature in these sections, which it will be understood are ordinarily made of relatively light sheet-metal, highly polished on their front faces.

Oscillatorily hung from ears 13, that depend upon the respective horizontally disposed ribs 4, is a curved, skeleton frame 14, that carries the lower approximately half-section 15 of the original parabolic reflector surface. Screws 16 passing through the aforesaid ears constitute trunnion bearings 15 for such lower reflector-section frame, and define its axis of oscillation, as will be hereinafter more fully explained.

For oscillating lower reflector-section frame 14 and holding it in desired position 20 about its axis, I preferably utilize a flexible wire 17, one end of which is attached to a lug 18 on the frame, while the other end is connected to an operating lever 19 on the steering post of the automobile, or else 25 where, (Figs. 7 and 8) as found most convenient, the intermediate portion of such wire being contained in a rigid tube 20, so that movement of the aforesaid lever will effect a corresponding movement of the reflector section.

As a matter of fact there will ordinarily be two head-lights, each provided with a reflector of the sort just described, so that a branched wire 17 will be necessary. It is 35 of course desirable that the reflectors in such case should be operated synchronously and by the same operating lever 19. Accordingly, I provide the coupling, shown in detail in Figs. 9 to 11, inclusive, for connecting the one branch of such wire to the other at a point intermediate between the lever and lamp. This coupling consists simply 40 of a sleeve 21, in which the two branch wires from the reflectors are received along with the single main wire from the operating lever, and there clamped in adjusted endwise relation by means of set-screws 22 threaded in such sleeve. The ends of the tubes 20, through which the respective wires 45 are carried, are clamped in opposite ends of a bracket 23, so as to leave a short section of each of the several wires free to be adjusted within the coupling.

For supporting the lamp-bulb 25, which 50 constituted the main source of light, (the use of a supplemental smaller lamp bulb 26 in a socket 27, therefor provided in rib 5, being entirely optional), I provide a holder 28 of the form clearly illustrated in Figs. 51, 2 and 3. This holder is formed with an axial bore adapted to receive and hold the lamp socket 29, the latter being held therein in longitudinally adjusted position by means of a set-screw 30, and correspondingly determining the longitudinal adjustment

of the lamp bulb, as will be readily understood. Holder 28 itself is attached to the lower portion of the vertical rib 5 of the fixed frame by means of a set-screw 31, passing through a slot in the holder, about which screw when loosened, said holder accordingly has a limited vertical, as well as an oscillatory movement, in a plane at right angles to the axis of the lamp. By virtue of this construction, the position of said lamp may be adjusted in three directions, in order to bring the filament in the lamp accurately to its proper working position in relation to the reflector.

In order both to steady the lamp bulb, and so securely hold it in such adjusted position, as well as to serve as a shield for certain of the direct rays emanating therefrom, a semi-circular plate 35 is supported in front of the upper portion of the lamp 85 by means of an arm 36 attached to this same holder through the medium of a set-screw 37. This plate is provided with a central aperture 38 near its lower edge that is adapted to engage the extreme tip or point 90 always found on a lamp bulb, and so prevents any displacement of such bulb, as might occur if it were somewhat loose in the socket, at the same time reducing breakage of filament due to wobbling of lamp.

Having thus described the principal mechanical features embodied in my improved head-light structure, the relative location and disposition of the several reflector-sections and the effect of such location and disposition in eliminating glare, and at the same time providing ample illumination of the roadway, may now be set forth.

The normal position of the lower reflector-section is, as shown in Fig. 3 and in full-lines in Fig. 5, with its lower edge moved slightly to the rear of the annular frame member. In this position the axis of such reflector-section coincides with what may be termed the normal horizontal axis, (see line 105 a—a, Figs. 4 and 5), in which, as heretofore stated, the axis of the lamp, or more especially the filament of such lamp, lies. The axis of oscillation of this lower reflector-section, as defined by its trunnion-axis 110 (see line b—b, Fig. 4) crosses the line of the axis a—a, just described, at right-angles, and the lamp should be adjusted longitudinally of the latter axis until its filament coincides with the point 40 of intersection. Then it will be obvious, that, in any position of the lower reflector-section, the light source defined by such filament remains at the focal point of the section in question. The tilting of the latter rearwardly into the 120 position shown in dotted outline at the right in Fig. 5 will accordingly direct the concentrated beam of light reflected from this portion of the lamp downwardly, but with undiminished brilliancy, while the same is 125 130

true if such beam be directed upwardly, by tilting the section in question into the position illustrated in dotted outline in the figure in question, at the left.

5 The section is thus tilted downwardly when it is desired to avoid striking an on-coming driver or pedestrian in the eyes, thereby causing the dangerous "glare" effect, while the beam will be directed upwardly 10 in approaching a hill or steep ascent which can obviously be only illuminated for a short distance by a horizontally directed beam. The normal position of the reflector will, of course, project a concentrated horizontal 15 beam, and will be used in driving ordinary level roads for distance seeing.

The two upper segmental sections 7 of the reflector, as previously indicated, are fixedly attached to the frame, but while portions of a parabolic surface, preferably the same as that of the lower section, these upper sections are mounted so as to lie with their axes (see lines *c-c*, Fig. 4) inclined to the normal axis *a-a* of the reflector hereinbefore referred to, and with their focal points or centers 41 displaced along such inclined axes a greater or smaller distance from the focal point or center 40 of the lower reflector section, with which, as previously stated, the source of light coincides. A smoother spread of light (one freer from dark spots) is thus obtained than would be possible by merely displacing the sections in lines parallel with the normal axis 35 of the device. An illustrative arrangement (for a reflector of given focus and a light source of given mass) of the axes of these two upper reflector sections and of the amount which their focal points may be thus 40 displaced, is illustrated in Figs. 4 and 5. By varying the inclination of the axes and the amount of this displacement, a great variety of illuminating effects may be procured from these upper reflector sections 45 without producing any so-called glare whatever, that is the light will be dispersed and directed so as to evenly illuminate a more or less extended area immediately in front of the automobile and of a width greater 50 than the roadway, so as to admirably serve the driver in noting irregularities or objects of danger close up to his machine.

Another source of glare I have found due to the construction of the lamp-bulb 42 55 itself, which, in the size most frequently employed in head-lights of the sort in hand, is spherical, with the filament 43 located forwardly of the center of the sphere, as illustrated in Fig. 6. The interior of the bulb 60 is a sufficient reflector to form in such case a phantom image of the filament displaced an equal distance from the center in the opposite direction, and this phantom image constitutes a secondary light source, with 65 which the reflector sections co-operate dif-

ferently than with the main light source constituted by the filament proper. I have accordingly found by experiment that, even where such main reflector sections be adjusted as hereinbefore described to avoid 70 any glare, a small beam of light is sometimes nevertheless received full in the eyes of a party approaching, such light coming from this secondary source. This difficulty may be obviated, of course, by locating the filament accurately in the center of the bulb, but this is not ordinarily feasible for manufacturing reasons, and I accordingly in such case introduce a light-absorbing element 44 75 of any suitable material, such as dark-colored asbestos or the like, which occupies the position where the phantom would be formed as illustrated in Fig. 6, and so effectively eliminates the latter.

Other modes of applying the principle of 80 my invention may be employed instead of the one explained, change being made as regards the mechanism herein disclosed, provided the means stated by any of the following claims or the equivalent of such stated 85 means be employed.

I therefore particularly point out and distinctly claim as my invention:—

1. In a lamp of the character described, the combination with a light source, of a 90 reflector comprising sections of a parabolic surface, said sections being bodily displaced longitudinally and laterally to bring their respective focal points rearward and laterally with respect to said light source, said 95 sections being also angularly disposed to each other to cause their respective axes to intersect in front of said light source.

2. In a lamp of the character described, the combination with a light source, of a reflector comprising sections of a parabolic surface, said sections being bodily displaced longitudinally and laterally to bring their 105 respective focal points rearward and laterally with respect to said light source, but 110 symmetrically disposed relatively to the same, said sections being angularly related to each other to cause their respective axes to intersect in front of said light source.

3. A reflector comprising a plurality of 115 sections of a parabolic surface having intersecting, angularly related axes lying in an approximately horizontal plane, said sections being bodily shifted to displace their 120 respective focal points equal distances to the rear of the point of intersection of their axes; and another section of a parabolic surface having its focal point intermediate of the focal points of said first-named sections.

4. A reflector comprising a plurality of 125 sections of a parabolic surface having intersecting, angularly related axes lying in an approximately horizontal plane, said sections being bodily shifted to displace their 130

respective focal points equal distances to the rear of the point of intersection of their axes; and another section of a parabolic surface having its focal point intermediate of 5 and to the front of the focal points of said first-named sections.

5. A reflector comprising a plurality of sections of a parabolic surface having intersecting, angularly related axes lying in an 10 approximately horizontal plane, said sections being bodily shifted to displace their respective focal points equal distances to the rear of the point of intersection of their axes; and another section of a parabolic 15 surface having its focal point intermediate of the focal points of said first-named sections, said last-named section being oscillatory about a transverse axis passing through its focal point.

20. 6. A reflector comprising two approximate quarter-sections of a parabolic surface having intersecting, angularly related axes lying in an approximately horizontal plane, said sections being bodily shifted to displace 25 their respective focal points equal distances to the rear of the point of intersection of their axes; and an approximate half-section of the same parabolic surface having its 30 focal point, intermediate of the focal points of said first-named sections.

7. In a lamp of the character described, the combination with a light source of a reflector comprising sections of a parabolic surface, two of said sections being disposed 35 with their axes in fixed angular relation to each other and being bodily shifted longitudinally of such axes to displace their respective focal points equal distances to the rear of the point of intersection of their 40 axes and thus symmetrically relative to the original focal point of such surface, and the third section having its focal point coincident with said light source.

8. In a lamp of the character described, 45 the combination, with a light source, of a reflector comprising sections of a parabolic surface, two of said sections being disposed with converging angularly related axes and being so displaced as to cause the intersection 50 of their axes and their respective focal points to be on opposite sides of said light

source, and the third section of said reflector having its focal point coincident with said light source, said last-named section being oscillatory about a transverse axis. 55

9. In a lamp of the character described, the combination with a light source, of a reflector comprising sections of a parabolic surface, two of said sections being disposed with converging angularly related axes and 60 being so displaced as to cause the intersection of their axes and their respective focal points to be on opposite sides of said light source, and the third section of said reflector having its focal point coincident with said 65 light source, said last-named section being oscillatory about a horizontal transverse axis passing through its focal point.

10. In a device of the character described, the combination of an outer casing; a two-part, rigid frame separate from said casing, one part of said frame being fixedly secured to said casing and the other part being connected to such first part so as to be oscillatory within said casing; and separate 70 reflector sections attached to the respective parts of said frame.

11. In a device of the character described, the combination of a light source; two fixed reflector sections consisting of approximate 80 quarter parts of a parabolic surface having their axes passing adjacent to said source at an angle to each other and to the normal axis of the device and having their focal points displaced relatively to said source; 85 and another reflector-section oscillatory about a transverse axis passing through said source and having its focal point approximately coincident with said source.

12. In a device of the character described, 90 the combination of a reflector, of a light source consisting of an incandescent electric lamp having an approximately spherical bulb and a filament displaced from the center thereof, and a light-absorbing body supported in said bulb at the point where a phantom image of said filament would be formed. 95

Signed by me, this 8th day of February, 1917.

OSCAR V. GREENE.
